UNITED STATES PATENT OFFICE.

SUMPTER L. HARWOOD, OF UNIONTOWN, ALABAMA.

SHAVING-CUP.

1,323,858.

Specification of Letters Patent.

Patented Dec. 2, 1919.

Application filed December 17, 1918. Serial No. 287,215.

To all whom it may concern:

Be it known that I, SUMPTER L. HARWOOD, a citizen of the United States, and a resident of Uniontown, in the county of Perry and State of Alabama, have invented a new and Improved Shaving-Cup, of which the following is a description.

My invention relates to a shaving cup and has for its general object to provide a shaving cup adapted to accommodate an insertible cartridge containing shaving cream and with a fountain thereon together with means to discharge the desired quantities of the cream into the fountain.

15 The above and other objects as well as the advantages of my improved construction will be explained in the specific description following.

Reference is to be had to the accompanying drawing forming a part of this specification, it being understood that the drawing is merely illustrative of one example of the invention.

Figure 1 is a side elevation of a shaving cup embodying my invention;

25 Fig. 2 is a bottom plan view;

Fig. 3 is a top plan view;

Fig. 4 is a longitudinal vertical section as indicated by the line $m-m$, Fig. 5.

30 Fig. 5 is a cross section taken through the line $m-m$, Fig. 4;

Fig. 6 is a side elevation of the insertible cartridge, part being broken away;

Fig. 7 is a plan view of the top or cap of the interchangeable cartridge;

Fig. 8 is a plan view of the piston;

Fig. 9 is a fragmentary vertical section of parts of the upper portion of the shaving cup taken in a plane corresponding with the line $x-x$, Fig. 4.

In carrying out my invention a cylindrical casing 10 is provided, having a permanent bottom 11 having a flange 12 suitably fastened to the body 10 at the lower edge.

15 The bottom 11 has a depression 13 and is perforated centrally of the depression to receive the unthreaded portion 14 of a screw 15 disposed axially in the body. Longitudinal movement of the screw is prevented by a collar 16 thereon in the depression 13 at the interior of the bottom 11 and operating disk 17 at the exterior of said bottom for turning said screw with which the operating disk is rigid. Said operating disk has 20 a depression corresponding with the depressed central portion of the bottom 11

and turns free of the disk 17 except at its central portion adjacent to the screw. At the periphery the disk 17 extends beyond the body 10 and is beaded as at 19 for convenient grasping. The top of the body 10 is threaded to receive a threaded flange of the cap 20, the center of which is perforated to accommodate a nozzle 21 on the insertible cylindrical cartridge 22, the said nozzle being formed on a cap 23 secured to the cartridge and formed at the edge 23 U-shaped in cross section to fit over the edge of the body of the cartridge. The bottom of the cartridge 22 consists of a piston 24 which when the cartridge is in place is adapted to be actuated by the screw 15 for extruding the shaving cream from the nozzle 21. The piston 24 is initially slightly larger in diameter than the internal diameter of the cartridge 22 and has a fluid-tight fit in the latter owing to the elasticity of the carton which may be formed of paper, the fluid tight fit being attained without the use of piston rings and by forming the edge 25 of the piston semi-circular in cross section to present a smooth interior surface to the cartridge and snugly engage the same. At the center the piston 24 is cupped as at 26 and perforated. The walls at the perforation are tinned and a nut 27 is cast in position from Babbitt metal, the threads being cast at the same time. In practice when the cartridge is made up the piston 24 constitutes the bottom thereof. A piece of tinfoil or the like is pasted over the nut so as to form a seal, but the seal may readily be punctured by the screw 15. For placing the cartridge in the casing 10 the cap 20 is removed and the nut 27 is caused to engage the threads of the screw 15 and the cartridge with its piston or bottom 24 turned until the cartridge is fully entered in the casing, resting against the bottom 11 after which the cap 20 is replaced so that the nozzle 21 of the cartridge will project therethrough.

A combined bowl and valve is employed as follows: The bowl 28 has centrally therein a nozzle 29 adapted to fit over and engage the threads of the nozzle 21 of the cartridge. At opposite sides the nozzle 29 is cut away obliquely as at 30 forming lateral discharge openings at each side. The transverse top 31 of the nozzle 29 extends across the top of the nozzle 21 and at the under side has a valve 32 of suitable yielding material adapted to bear against the

top of the nozzle 21, the latter having a discharge orifice 33 centrally therein at the top. The arrangement is such that the bowl 29 may be screwed tightly onto the 5 nozzle 21 so that the valve 32 will close the discharge orifice 33 whereas a slight turning back of the bowl 28 will raise the valve 32 and permit outflow of the shaving cream through the orifice 33 and 10 through the beveled sides 30 of the nozzle 29. The arrangement leaves a clear opening when the valve is raised and there is not presented such a discharge opening as would be clogged by the hardening of the 15 shaving cream. At the same time shaving cream extruded into the bowl 28 may be freely used with water as desired when the valve is again closed by the screwing down of the bowl and said bowl may finally 20 be washed without danger of the moisture getting into the body of the cream in the cartridge.

The disk 17 is formed with a hole or holes 18, there being a similar hole or holes 25 in the bottom 11, in order that the user of the cup may observe the position of the piston 24 to thereby ascertain the approximate quantity of material remaining in the cartridge 22. The length of the screw 15 30 relatively to the cartridge 22 is such that if the piston 24 should be advanced to a point to be arrested by the top 23 so that no further movement of the piston could take place in response to the turning of 35 the screw, then a few threads only would be stripped from the nut 27 since the major portion of the threads of the nut 27 will have passed beyond the screw. Thus, the stripping of the soft threads of the nut prevents 40 damage to the device as a whole by an excessive turning of the screw.

The cylindrical body of the cartridge 22 is preferably formed of paper lined with two layers of very thin tinfoil, the two layers insuring a perfect lining since the one layer of tinfoil may have punctures produced therein during the process of manufacture. The inner layer of tinfoil is cemented to the wall of the cartridge and 45 50 the two layers are cemented to each other. The cartridge is formed of a diameter to slip loosely into the body 10 and extended a proper length to clamp between the top and bottom of the casing when the top is 55 screwed down.

I would state in conclusion that while the illustrated example constitutes a practical embodiment of my invention, I do not

limit myself strictly to the mechanical details herein illustrated, since manifestly the 60 same can be considerably varied without departure from the spirit of the invention as defined in the appended claims.

Having thus described my invention, I claim as new, and desire to secure by Letters Patent:

1. A shaving cup including a container adapted to hold a supply of shaving cream, a nozzle on the container, a bowl on said container and to which said nozzle discharges, and valve means controlling said nozzle to establish or disestablish communication between the nozzle and bowl.

2. The combination with a container and a nozzle for the discharge of the material 75 from the container, of a bowl positioned to receive the material discharged by the nozzle and movable relatively to said nozzle, and valve means associated with said bowl and controlling said nozzle by the relative 80 movement of the bowl.

3. In a device of the class described employing a container, a nozzle for the discharge of material from the container, a bowl positioned to receive the material discharged by said nozzle, and a nozzle in the bowl and fitting on the first nozzle, the nozzle on the bowl having sloping sides formed with outlets, and a valve on the nozzle of the bowl to close or open the first 90 nozzle by turning movement of the bowl and its nozzle relatively to the first nozzle.

4. In a device of the class described, a container, a piston operating therein and having a central nut of soft metal rigid 95 with said piston, a screw extending axially in the container and through said piston in threaded engagement with the latter, and means to turn said screw for advancing the piston, said screw terminating short of the 100 end of the container a distance to cause the piston to partially disengage itself from the threads of the screw when the piston has reached the end of the container.

5. In a device of the class described, a 105 container a removable cartridge therein, a nozzle on said cartridge, a removable cap on the end of the container through which cap said nozzle extends, a bowl having a nozzle screwing onto the first nozzle, valve 110 means associated with the second nozzle to close or open the first nozzle, and means to cause discharge of material from said cartridge through said nozzles.

SUMPTER L. HARWOOD.
